(57) **CLAIM**

What is claimed is the ornamental Design for a GPS receiver, as shown and described.

DESCRIPTION

FIG. 1 is a perspective view of a preferred embodiment of a GPS Receiver.

FIG. 2 is a bottom view of the GPS receiver of FIG. 1.

FIG. 3 is a top view of the GPS receiver of FIG. 1.

FIG. 4 is a front view of the GPS receiver of FIG. 1.

FIG. 5 is a first side view of the GPS receiver of FIG. 1.

FIG. 6 is a second side view of the GPS receiver of FIG. 1.

FIG. 7 is a rear view of the GPS receiver of FIG. 1.

The broken lines in the figures form no part of the claimed design.
